UNITED STATES PATENT OFFICE.

JOSEPH B. STRAUSS, OF CHICAGO, ILLINOIS, ASSIGNOR OF ONE-HALF TO CHARLES WEINFELD, OF CHICAGO, ILLINOIS.

CONCRETE CAR.

Application filed August 27, 1920. Serial No. 406,879.

To all whom it may concern:

Be it known that I, JOSEPH B. STRAUSS, a citizen of the United States, residing at Chicago, in the county of Cook and State of Illinois, have invented a certain new and useful Improvement in Concrete Cars, of which the following is a specification.

This invention relates to concrete cars and has for its object to provide a new and improved device of this description. The invention has among other objects, to provide a car having a concrete body formed to stand the strains and stresses and rough uses to which cars are subjected, and which shall at the same time, be cheap to construct and comparatively light in weight. The invention has other objects which are more clearly pointed out in the following description.

Referring now to the accompanying drawings which show the construction embodying my invention,

Figure 1 is a plan view in part section of the body of the car;

Figure 2 is a view of one form of end for the body of the car;

Figure 3 is a section view taken on the line 3—3 of Figure 1;

Figure 3^a is a view similar to Figure 3 showing a modified construction;

Figure 4 is a section view taken on the line 4—4 of Figure 1;

Figure 5 is a section view through one of the stakes;

Figure 6 is a section view showing a modified construction of the stake;

Figure 7 is a view showing one method of connecting the reinforcing metal in the stakes or ribs to the metal frame work;

Figure 8 is a section view taken on the line 8—8 of Figure 3 with the bolster portion turned up on top;

Figure 9 is a section view taken on the line 9—9 of Figure 1 with the concrete omitted showing the reinforcing members;

Figure 10 is a similar view taken on the line 10—10 of Figure 4;

Figure 11 is a similar view taken on the line 11—11 of Figure 1;

Figure 12 is a view showing the metal underframe on which the concrete body is mounted;

Figure 13 is a section on line 13—13 of Figure 12;

Figure 14 is a view on the line 14—14 of Figure 12;

Figure 15 is a section on the line 15—15 of Figure 14;

Figure 16 is a section on the line 16—16 of Figure 12.

Figure 17 is a view of the metal underframe showing a modified construction;

Figure 18 is a view of one end of the metal underframe showing a modified construction;

Figure 19 is a sectional view through a portion of the bottom of the car showing a modified construction at the location of line 19—19 of Figure 17;

Figure 20 is a view taken on line 20—20 of Figure 18;

Figure 21 is a view in part section showing the corner construction where the side and removable end meet;

Fig. 22 is a sectional view showing a modified construction.

Figure 23 is a section view showing a door in the bottom of the car.

Figure 24 is a plan view of the same.

Like numerals refer to like parts throughout the several figures.

Referring now to the drawings, I have shown a construction where a reinforced concrete body is made separate from the metal underframe and is then placed upon this underframe and fastened thereto. The metal underframe may be of any desired construction corresponding to that made by the Master Car Builders' specifications. In Figure 1, I have shown the body made of reinforced concrete and having a bottom 1, and side walls 2, and ends 3. The bottom and side walls are preferably integral while the ends may be separate and removably attached in position if desired so that if injured, they can be easily replaced. The side walls are provided with a series of ribs or stakes 4, which connect with the bottom and which are provided with reinforcing metal 5. These stakes are both on the outside and inside and are shown in detail in Figure 6. There are inclined ribs or stakes 6, which preferably connect with the vertical ribs or stakes 4, and which also contain reinforcing material 7. The upper edges of the body are provided with metal frame pieces 8 which are shown as chan-

nels and these metal frame pieces are connected to the reinforcement. In Figure 7, I have illustrated one method of doing this wherein the reinforcing metal members 5 and 7 are connected to the frame piece 8 by means of nuts 9. The stakes instead of being both on the outside and inside may be only on one side as shown in Figure 5, and are provided with the reinforcing metal pieces 5. These reinforcing metal pieces are tightened together by reinforcing metal 10. The bottom and sides have other metal reinforcement 12. I also prefer to provide the bottom, sides, and ends with wire mesh or net work reinforcement 13, and this reinforcement is connected with the longitudinal metal members 8 at the top and 14 at the bottom of the side walls and ends. The metal underframe is made up of the center sills 15 and bolsters 16, one at each end and metal cross bearers 17. The concrete body has the longitudinal metal members at the edges thereof and there are cross members 18 associated with the floor and connected with the longitudinal metal members. This connection is made in any desired manner as by plates 19 and suitable rivets, and these cross members are also connected with the longitudinal metal members 14 of the body by suitable plates 20. The center sills are preferably made up of metal parts as illustrated in Figures 3 and 12 and 13, although any other suitable construction may be used. The ends may be integral with the sides and floor of the body or they may be separate as illustrated in Figure 2 where I have shown an end 22 having the upper and lower metal bounding members 8 and 14 and the stakes with the various reinforcing metal rods embedded in the concrete. When separate ends are used, they are arranged so that they may be removably connected with the walls and bottom so that they can be disconnected for purposes of replacement. Such ends are provided with limiting metal members on both the top and bottom and the other edges, these other metal members being shown at 24. These metal members are removably connected to the side walls of the car by suitable connecting pieces 38 as shown in Figures 1 and 21. I may also provide pipes 28 for fluid which may be embedded in the floor of the car and extend longitudinally and cross-wise and I can use them as pipes and also as reinforcing metal. These pipes may be provided for air and steam. For example, at certain times, it is desirable to heat by steam within the car and steam can be then sent through these pipes for that purpose. In Figures 17 and 18, I have shown a modified construction where there is a metal longitudinal sill 30 and metal cross bearers 31 and bolsters 32.

In Figures 19, 20, 21, and 22, I have shown details of this construction wherein there are concrete cross bearers 33 integral with the body and with the sides of the car and each provided with a metal member 34 connected by reinforcement 35 with the reinforcement 36 in the floor. Figure 21 shows the removable ends connected by the plates 38 with the sides.

Figures 23 and 24 show the concrete door 39 with the metal bounding edges 40 and hinges 41. It will be noted I have here shown a construction of a concrete car comprising a metal center sill and bolsters, a concrete body comprising a floor, longitudinal metal members at the edges thereof, cross members associated with said floor and connected to the longitudinal metal members, reinforcement connected to the two sets of metal members, concrete embedding said reinforcement and contained between the longitudinal members, concrete sides and ends connected with said floor, said sides and ends comprising longitudinal metal members, reinforcement connected thereto and to longitudinal metal members of the floor and concrete embedding said reinforcement and contained within the limits of the longitudinal metal members, and connecting means such as the plates 20 for connecting the concrete body as a whole to the center sill and bolsters.

From the foregoing it will be seen that applicant has a metal underframe and a concrete body having a floor and sides and ends of concrete. The body may be separate from the underframe, and may be constructed separate therefrom, and then placed on the metal underframe and connected therewith. It will further be seen that there are separate metal members or connecting pieces 20 connected with the bottom or floor of the body, and by means of which, through suitable bolts or the like, the body is connected with the sills and bolsters. The cross bearers or cross members of the underframe may be attached to the longitudinal sill 30, as shown in Figure 18, or may be separate from the center sill 15 and attached thereto by the fastening plates 19 as shown in Figure 3. When this construction is used the cross pieces 18 may be fastened to the center sill 15 before the body is placed thereon, or they may be attached to the body by the connecting pieces 20, and then fastened to the sill 15 after the body is placed thereon. Different forms of stakes are shown, the stakes projecting on one side only being shown in Figure 5, and the stakes projecting on both sides being shown in Figure 6.

Figures 1 and 4 show the body without the concrete cross bearers, while Figure 19 shows it with these cross bearers 33. These

concrete cross bearers will be used where desired and omitted when it is not desired to use them.

I claim:

5. 1. A concrete car comprising a metal underframe comprising metal bolsters and metal cross bearers, a reinforced concrete body having integral sides and bottom separate from said metal underframe and mounted thereon, and connecting means for connecting the concrete body with said underframe. 70
10. 2. A concrete car comprising a metal underframe, a concrete body mounted upon said underframe, said body comprising reinforced concrete side walls and reinforced concrete end walls separate from said side walls, limiting metal members for said separate concrete ends by means of which they 75
15. 20. are held in place, and connecting means for removably connecting said end walls and side walls so that they may be disconnected for purposes of replacement. 80
25. 3. A concrete car comprising a body having a bottom and side walls of reinforced concrete, the bottom and side walls being integral, reinforced concrete end walls separate from said bottom and side walls, and means for removably connecting said end 85
30. 30. walls with said bottom and with the side walls so that they may be disconnected for purposes of replacement. 90
35. 4. A concrete car comprising metal sills cross bearers and bolsters, a reinforced concrete body mounted thereon, a floor forming a part of said body, separate metal members connected with the floor on the line of the sills cross bearers and bolsters, and means for connecting said metal members to 95
40. 40. said sills cross bearers and bolsters. 100
45. 5. A concrete car comprising metal sills cross bearers and bolsters, a concrete body mounted thereon comprising reinforced concrete side walls and reinforced concrete end walls, limiting metal members within which said end walls are contained, a floor also contained within said limiting members, separate metal members connected with the floor on the line of the sills cross bearers and 105
50. 50. bolsters, and means for connecting said metal members in the floor to the sills cross 110
55. 6. A concrete car comprising a metal underframe, a concrete body mounted thereon, said concrete body having reinforced concrete side walls, end walls for said body, limiting metal members for said walls including top and bottom longitudinal members, transverse members connected to said 115
60. 60. longitudinal members at intervals, and reinforcing steel members between said longitudinal members. 120
65. 7. A concrete car comprising a metal underframe, a reinforced concrete body having reinforced end walls and reinforced side 125
- walls, said body separate from said metal underframe and mounted thereon, certain of said walls being separate from the body portion and connecting means for removably connecting said separate walls to said body so that they may be disconnected therefrom for purposes of replacement. 130
8. A concrete car comprising metal sills and bolsters, a reinforced concrete body mounted thereon, a body comprising walls contained between limiting steel members, stakes on said walls, cross bearers associated with said stakes and connecting the side walls and the center sill and a separate floor over the sills and cross bearers. 80
9. A concrete car comprising metal sills and bolsters, a reinforced concrete body mounted thereon, side walls and a floor forming a part of said body, cross bearers associated with the floor and the metal sills, stakes associated with the walls, said stakes tied in to the cross bearers at one end and the top flange of the wall at the other end, part of said stakes being on the inside and part on the outside of said walls. 90
10. A concrete car comprising a metal center sill and bolsters, a concrete body comprising a floor, longitudinal metal members at the edges thereof, cross members associated with said floor and connected to the longitudinal metal members, reinforcement connected to the two sets of metal members, concrete embedding said reinforcement and contained between the longitudinal metal members and connecting means for connecting the concrete floor as a whole to the center sill and bolsters. 100
11. A concrete car comprising a metal center sill and bolsters, a concrete body comprising a floor, longitudinal metal members at the edges thereof, cross members associated with said floor and connected to the longitudinal metal members, diagonal metal members connected to the longitudinal metal members, reinforcement connected to the two sets of metal members, concrete embedding said reinforcement and contained between the longitudinal metal members, and connecting means for connecting the concrete floor as a whole to the center sill and bolsters. 105
12. A concrete car comprising a metal center sill and bolsters, a concrete body comprising a floor, longitudinal metal members at the edges thereof, cross members associated with said floor and connected to the longitudinal metal members, reinforcement connected to the two sets of metal members, concrete embedding said reinforcement and contained between the longitudinal metal members, concrete sides and ends connected with said floor, and connecting means for connecting the concrete body as a whole to the center sill and bolsters. 110
13. A concrete car comprising a metal

center sill and bolsters, a concrete body comprising a floor, longitudinal metal members at the edges thereof, cross members associated with said floor and connected to the longitudinal metal members, reinforcement connected to the two sets of metal members, concrete embedding said reinforcement and contained between the longitudinal members, concrete sides connected with said floor, and integral therewith, and connecting means for connecting the concrete body as a whole to the center sill and bolsters.

14. A concrete car comprising a metal center sill and bolsters, a concrete body comprising a floor, longitudinal metal members at the edges thereof, cross members associated with said floor and connected to the longitudinal metal members, reinforcement connected to the two sets of metal members, concrete embedding said reinforcement and contained between the longitudinal members, concrete sides connected with said floor, and integral therewith, said sides and ends comprising longitudinal metal members, reinforcement connected thereto and to longitudinal metal members of the floor and concrete embedding said reinforcement and contained with the limits of the longitudinal metal members, and connecting means for connecting the concrete body as a whole to the center sill and bolsters.

15. A concrete car comprising concrete floor, walls and ends, longitudinal metal members at the top and bottom of said walls and ends, and a connecting system comprising metal rods part diagonal and part vertical, a reinforcing metal network also connecting the longitudinal metal members,

concrete embedding said rods and metal network, the concrete thickened along the length of the diagonal and vertical rods. 40

16. A concrete car comprising concrete floor, walls and ends, longitudinal metal members at the top and bottom of said walls and ends, and a connecting system comprising metal rods part diagonal and part vertical, a reinforcing metal network also connecting the longitudinal metal members, concrete embedding said rods and metal network, the concrete thickened along the length of the diagonal and vertical rods, the thickened concrete sections having rounded edges. 45 50

17. A concrete car comprising concrete floor, walls and ends, longitudinal metal members at the top and bottom of said walls and ends, and a connecting system comprising metal rods part diagonal and part vertical, a wire network also connecting the longitudinal metal members, concrete embedding said rods and wire network, the top longitudinal member comprising a channel section with the flanges down and the bottom longitudinal members an angle with a flange turned up, the thickened concrete sections having rounded edges. 55 60 65

18. A concrete car comprising a concrete body portion, sills and bolsters therefore, and fluid conducting pipes embedded in the concrete of said body portion and also forming a part of the reinforcing system for the concrete. 70

Signed at Chicago county of Cook and State of Illinois, this 16th day of August, 75 1920.

JOSEPH B. STRAUSS.
